US0D1097586S

(12) **United States Design Patent** (10) **Patent No.:** **US D1,097,586 S**
(45) **Date of Patent:** **** Oct. 14, 2025**

(54) **TOOTHBRUSH HEAD**

(71) Applicant: **The Gillette Company LLC**, Boston, MA (US)

(72) Inventors: **Uwe Jungnickel**, Koenigstein (DE); **Dominik Langhammer**, Frankfurt (DE)

(73) Assignee: **The Gillette Company LLC**, Boston, MA (US)

(**) Term: **15 Years**

(21) Appl. No.: **29/787,707**

(22) Filed: **Jun. 8, 2021**

Related U.S. Application Data

(63) Continuation of application No. 29/659,068, filed on Aug. 6, 2018, now Pat. No. Des. 960,581.

(30) **Foreign Application Priority Data**

Feb. 9, 2018 (WO) IB6333101

(51) **LOC (15) Cl.** **28-03**

(52) **U.S. Cl.**

(57) **CLAIM**

The ornamental design for a toothbrush head as shown and described.

DESCRIPTION

FIG. 1 is a perspective view of a toothbrush head;

FIG. 2 is a front view thereof;

FIG. 3 is a right side view thereof;

FIG. 4 is a rear view thereof;

FIG. 5 is a left side view thereof;

FIG. 6 is a top plan view thereof; and,

FIG. 7 is a bottom view thereof.

Broken lines are used in the drawings to designate environmental structures or parts of an electric toothbrush that form no part of the claim.

1 Claim, 1 Drawing Sheet
